UNITED STATES PATENT OFFICE.

HANS MIKOREY, OF SCHÖNEBERG, NEAR BERLIN, GERMANY.

COLOR-SPRAYING APPARATUS.

No. 883,144.

Specification of Letters Patent. Patented March 24, 1903.

Application filed May 27, 1907. Serial No. 375,933.

To all whom it may concern:

Be it known that I, HANS MIKOREY, a civil engineer and a subject of the German Emperor, and a resident of 13 Wartburg-5 strasse, in the city of Schöneberg, near Berlin, Kingdom of Prussia and German Empire, have invented a certain new and useful Color-Spraying Apparatus, of which the following is a specification.

- 10 This invention has reference to a spraying apparatus, which is particularly intended for the spraying or disintegrating of colors or dye stuffs and which is distinguished by a peculiarly shaped dashing or abutting plate.
- 15 Atomizers or sprayers in combination with abutting surfaces have already been variously suggested; these abutting or dashing surfaces however did not serve the purpose of disintegrating or spraying, but they merely
- 20 served for the deflection of an already atomized jet from its original direction or for the regulation of the efficient coloring substance. Thus for instance, one of the sprayers or disintegrators or atomizers now in use, possesses
- 25 a gutter shaped abutting surface, which however does not participate in the distribution of the color or dye-stuff, but which serves exclusively for the purpose of deviating the current of air which is already charged with the
- 30 disintegrated color, in any desired direction. In another atomizer or sprayer, which is arranged, so as to form part of a machine, and which serves for the automatic production of different shades of colors blended into each
- 35 other, dashing or abutting surfaces are provided at an angle to the direction of the current of air. These abutting or dashing surfaces are so near to the surface to be covered with color and they are arranged at such a
- 40 distance from the air delivering nozzle, that the color is merely reflected in a certain direction, the current of air having no further influence upon the movement of the deflected particles of color or dye stuff. The particles
- 45 of color on the contrary continue their way in the direction, imparted to them by the inclination of the abutting or dashing surface and are thrown upon the surface to be covered with color, in regulated proportion. Ac-
- 50 cording to the inclination of the dashing or abutting plate and the thereby resulting angle of deflection, which is different for the different parts of the cone of jets striking against the abutting body, the same amount
- 55 of color will be distributed upon a larger or smaller number of surface units of the sur-

face to be colored, and the blending of shades of color is thereby accomplished. Furthermore, a device for the moistening of textile fabrics, which works without disintegration, 60 has been suggested heretofore, in which a cone is arranged in front of a jet throwing nozzle. This cone is likewise merely a directing surface for the purpose, to expand a cylindrical jet of water into a hollow cone of 65 water, closed all around. As compared with these well known constructions, the herein described sprayer or atomizer, which is intended for manual operation is distinguished by the fact, that the abutting or dashing 70 plate is arranged substantially vertically in relation to the direction of the air current, in order to contribute to the increase of the spraying action and with a view of producing as fine a mist of color as possible.

75 The abutting or dashing plate is very narrow in one of its two dimensions and at right angle to the direction of the impinging air current and it is also arranged near to the air and color delivering nozzle; hence the mist of 80 color, originated from the abutting or dashing surface is still struck by the air current issuing from the air pressure nozzle, so that a certain definite direction, which is approximately that of the air current can be imparted to the entire mass of the mist. On the 85 surface on which the mist of color impinges and which is to be coated, the color is put on everywhere at a uniform thickness. The graduation of shades of color for obtaining 90 artistic effects is done by hand, so that artistic individuality can be imparted to the work.

95 On the drawing an embodiment of the subject matter of the invention is shown by way of example, *a* being the color delivering nozzle, which is arranged above the pressure air nozzle *b* in the well known manner. In front of the nozzle *b* the abutting or dashing plate *d* of little height and of suitable breadth 100 is arranged which might be exchangeably secured in such a manner, that the jet of air and of color of dye stuff will strike against it in a vertical or approximately vertical direction.

105 In order to be able to change the efficiency of the spraying or disintegrating action by inclining the abutting or dashing plate or by moving it up and down, the dashing plate is preferably connected to a spring acting plate 110 *c* or made in one piece with the same. By means of a set screw *s* connected in a suitable

manner to the nozzle pipe *b*, the plate *c* and consequently the abutting or dashing plate *d* also may be differently inclined or adjusted in a vertical direction.

- 5 The arrangement of the abutting or dashing plate *d* is also applicable in the case of color or dye-stuff disintegrators, in which the color delivering nozzle is arranged below the air pressure nozzle.
- 10 What I claim and desire to secure by Letters Patent of the United States is:—

Sprayer for liquid colors comprising a color tube *a* and an air tube *b* arranged at an angle to each other, a resilient dash plate *c* secured

15 to the nozzle *b* near the opening of the nozzle *a*, with a deflector *d* in line with the nozzle *b*, a set screw *e* in a bar rigidly connected to the nozzle *b* and adapted to act on the dash plate *c* substantially as described and for the purpose set forth.

20 In witness whereof I have hereunto signed my name this eighth day of May 1907, in the presence of two subscribing witnesses.

HANS MIKOREY.
